UNITED STATES PATENT OFFICE.

SAMUEL F. GREENE, OF IRVINGTON, NEW JERSEY.

MOLD FOR TYPE-CASTING MACHINES.

1,280,717.

Specification of Letters Patent.

Patented Oct. 8, 1918.

Application filed May 29, 1917. Serial No. 171,622.

To all whom it may concern:

Be it known that I, SAMUEL F. GREENE, a citizen of the United States, and resident of Irvington, in the county of Essex and State 5 of New Jersey, have invented certain new and useful Improvements in Molds for Type-Casting Machines, of which the following is a specification.

In the art of printing it is necessary that 10 means be supplied for filling up the blank spaces in the forms between and around the printed matter or illustrations. For this purpose, the printer uses blocks of metal of various sizes and shapes which are known as 15 slugs, quads, leaden rules and quotations according to their particular size and shape. Some of these, namely the slugs, leaden rules and quads may be and generally are cast on type casting machines, but the quotations, 20 being the largest filling members, are made in type foundries. When made of iron they require additional careful squaring and planing. Inasmuch as nearly all printing establishments, even those of moderate size, 25 employ type-casting machines on their premises, it is an obvious advantage for them to be able to cast their quotations on the type casting machines instead of having to obtain them from outside sources, from 30 which the supply may not always be available. Another advantage is that the printer is then able to cast quotations in the sizes most needed, or cast them in special sizes as requirements demand. Heretofore it has 35 been impossible to cast quotations on type-casting machines and in view of the foregoing it is the main object of this invention to provide a mold adapted to be used on existing types of type-casting machines for the 40 purpose of casting hollow quotations of all sizes.

Type-casting machines as arranged at present cannot cast types larger than thirty-six points, and leaden rules, slugs or quads 45 up to twelve points only. It is one of the objects of this invention to provide a mold adapted to cast quotations in sizes from thirty-six points and up to seventy-two points square. 50 Another object of the invention is to provide a mold for this purpose as a separate article of manufacture adapted to be attached to a type-casting machine without altering the construction thereof except in 55 minor details not affecting its efficiency or limiting its uses. Another object of the in-

vention is to provide a mold for casting quotations which may be used in combination with a type casting machine and some of its attachments provided for casting 60 leaden rules for instance.

Accordingly, my invention is embodied in a mold constructed and arranged as herein-after set forth and illustrated in the accompanying drawings, together with such attachments as are required for the operation of the mold on a type-casting machine. In the said drawings—

Figure 1 is a perspective view of a mold embodying my invention. In this view the 70 centering pin is shown elevated above the mold for the sake of clearness;

Fig. 2 is a plan view of the mold showing the same attached to a type-casting machine and with certain parts removed; 75

Fig. 3 is a front elevation of the mold looking in direction of arrow 3 in Fig. 2;

Fig. 4 is a view of certain parts of the mold looking in the direction of the arrow 4 in Fig. 2 and showing the mold itself in 80 section;

Fig. 5 is a sectional view of the mold on line 5—5 of Fig. 2;

Fig. 6 is a perspective view of the mold blade detached; 85

Fig. 7 is a perspective view of one of the interchangeable mold blade heads;

Fig. 8 is a plan view of the type pusher operating lever detached; and

Fig. 9 shows two sizes of quotations produced by the mold. 90

Referring to Figs. 1, 4 and 5, my improved mold is preferably made of steel and comprises a base 10 which forms the bottom portion 11 of the mold proper which is 95 designated by the numeral 12. The mold base supports the several parts of the mold. The mold 12 is square and is formed of four elements. One of these is the fixed base portion 13, Fig. 4, which forms the one mold 100 side or wall 14. The opposite wall 15 is formed by the element or mold wall piece 16, which is laterally adjustable against an adjustable stop 24 by means of the slots 17, 17 and the screws 18, 18 screwed into the 105 base. The third mold wall is formed by the mold blade abutment 19 which reciprocates to open and close the mold as will be described hereinafter. In closing the mold the edge 20 of the abutment enters a notch 21 in the mold wall 14. The fourth mold wall or side is formed by the mold blade

head 22 carried by the mold blade 23. The top of the mold is closed by the centering pin head 25 supported on the centering pin 26.

5 Fig. 1 shows the mold closed and ready for casting, except that the centering pin is shown in elevated position for the sake of clearness. Fig. 4 shows in sectional view the mold closed and the quotation 27 cast 10 therein.

The operation is as follows: After the mold has been closed, the metal is pumped into it through the mold hole 28 in the bottom and in the same manner in which the 15 metal is pumped into the ordinary type mold. When the quotation has been cast, the mold is opened by elevating the centering pin and moving the mold blade abutment 19 to one side, to the left in Fig. 1.

20 Thereafter, the mold blade moves forward or to the right, into and through the mold and pushes the cast quotations out of the mold and in front of the type pusher 30. As the quotation leaves the mold it is moved 25 over a small lug 31 and thereby tipped so as to free it completely from the mold blade head 22 and the mold, for which purpose the said head is also provided with a central projection 32, see Figs. 2 and 5. By 30 these means a clean break between the cast quotation and the mold is obtained.

The type pusher 30 is a reciprocating element which slides on the mold base 10 between the mold portion 13 and a fixed guide 35 member 34. Overhanging guide strips 35, 35 keep the type pusher in position. When the cast quotation has been moved in front of the type pusher, the latter is moved to the left, in Fig. 1, and pushes the finished 40 quotation to one side of the mold and forward on the base 10. The face 36 of the type pusher is inclined so as to move the quotation away from the mold in an oblique direction as is obvious. While the type 45 pusher is removing the quotation, the abutment 19 is again moved to close the mold, the mold blade is moved to the left to uncover the hole 28, the centering pin descends to close the mold and another quotation 50 is cast.

In order to operate the mold as aforesaid, the several parts thereof are connected to those elements of the type casting machine which operate corresponding parts in the 55 ordinary type molds, and the mold as an article of manufacture and commerce is designed so as to be attached to the type-casting machine very quickly and without requiring the use of any special tools. The 60 mold and its several parts are positioned on the type-casting machine and attached thereto in the following manner, the type-casting mold having first been removed.

The typecasting machine is represented 65 in Figs. 2 and 3, by a portion of its frame-

work 40. 41 is the galley pan bracket. In this instance the latter supports a pan or tray 42 which receives the cast quotations as they come from the mold and are pushed to one side by the type pusher. 43 is a bolt 70 which passes through a portion of the frame 40 and bears against the mold base 10 to secure the same in position. I may use other bolts, not shown, which are arranged according to the shape of the type-casting 75 machine.

The numeral 45 denotes the center pin operating lever of the machine. 46 is a bracket secured to said lever when the leaden rule mold of the machine is used. In the 80 said bracket, which herein is treated as a part of the center pin operating lever, I drill two holes for the bolts 47, 47 with which I attach a bracket 48 to the lever. To the bracket 48 is secured in turn the center pin 26 as shown in Figs. 3 and 4. Fig. 1 does not show the center pin operating lever and the center pin.

The particular construction of the center pin is as follows: At the lower end the pin 90 is provided with a ball and socket joint composed of the ball 49 and the socket member 50, which is held onto the ball by the square split collar 51. The socket member has a tongue 52 which enters a recess 53 in the ball 95 to prevent relative turning of these two parts. The center pin head or male mold member 25 is detachably carried by the socket member 50 by a tongue and groove connection 54 and is provided with a flange 100 55 adapted to rest upon the mold. The center pin extends up through an upper guide link 56 which is secured to the bracket 48 by a wing bolt 57. A spring 58 is interposed between the center pin and the link 105 56. 59 is a lower guide link secured to the mold at 60, see Figs. 2 and 3, and which link is pivoted at 61 to a sleeve 62 surrounding the center pin. It will therefore be seen, that the center pin may be accurately adjusted in position over the mold by swinging the upper and lower links 56 and 59 on their pivots at 57 and 60 respectively. The mold itself is placed so that the mold hole 28 comes within a cut out portion 64 in the 115 frame of the machine, into which cut out portion the nozzle 65 projecting upward from the melting pot 66 is moved, and so that when the nozzle is raised it fits into the said hole 28.

The type pusher 30 is operated from an arm 67, pivoted to the mold base at 68, by means of the screw 69 and slot 70 in said arm. The free end of the arm is connected at 71 to the type pusher operating lever 72, shown in Fig. 8, which in turn is connected to the type pusher bell crank on the machine which is well known to those skilled in the art and therefore not shown.

The mold blade is provided with a hole 130

73 into which fits a stud 74 on the mold blade operating slide 75 which is also a part of the machine. The mold blade is operated against the micrometer stop attachment 76 5 on the type-casting machine. The heads 22 on the mold blade are of different sizes depending upon the size of quotation to be cast and the head is secured to the blade by screws 77. 78 is a top guide piece for the 10 mold blade 23.

The mold blade abutment 19 slides between the mold member 16 and a guide piece 79 and underneath suitable guide strips 80 and 81 which extend from a bearing 82. To 15 the latter is pivoted at 83 a rock arm 84. One end of the rock arm is connected at 85 to a link 86 pivoted at 87 to the abutment 19. To the other end of the arm is pivoted a curved link 88 which in turn is connected 20 to the connection 89 carried by the centering pin operating lever as a part of the type-casting machine.

The center pin operating lever oscillates in a vertical plane. When it descends it 25 centers the male mold member 25 in the mold 12, being guided in its downward movement by the sleeve 62. At the same time the connection 89 depressed the curved link 88, thereby rocking or oscillating the 30 rock arm 84, raising the pivot 85 and through the link 86 moving the mold blade abutment 19 to close the mold. Both the male mold member and the link 88 are depressed under spring pressure as is obvious 35 from the drawing. Also at this time, the mold blade operating slide 75 moves to the left in Figs. 2 and 3, thereby uncovering the mold hole 28. The limit of this movement is reached when the end of the mold blade 40 strikes the micrometer stop.

The finished cast quotations are shown in Fig. 9. There may be several sizes because of the adjustability of the mold, which may be made wider by adjusting the position of 45 the part 16, and made longer by adjusting the micrometer stop 76. During the casting, the type pusher operating lever actuates the type pusher to remove the finished quotation.

50 Preferably the mold is cooled by passing water from the water connection 92 on the machine through water channels 93 in the mold piece 13, see Fig. 2.

From the foregoing it will be seen that I 5 have provided a mold for casting quotations on a type casting machine, adapted to be attached to the latter and operated in combination therewith. Besides the mold as shown in Fig. 1, the invention comprises the 60 centering pin and type pusher operating lever as actuating parts of the mold.

While I have shown my invention in its preferred form, I do not wish to be limited thereto except as required by the scope of 65 the appended claims.

I claim.

1. The combination with a typecasting machine, of a mold for casting quotations and comprising a base, two opposed fixed mold members, a mold blade abutment for closing the space between the said members at the one end thereof, a mold blade, a centering pin, a centering pin head carried by said centering pin and adapted to extend into the said mold and close the same, means 75 for operating said mold blade to eject the cast quotation from the mold and means for operating the said centering pin.

2. The combination with a typecasting machine and its mold operating mechanism, 80 of a mold for casting quotations, means for securing the said mold to the said machine, said mold comprising two opposed fixed mold members, a first mold member for opening and closing one end of the mold, a second member for opening and closing the top of the said mold, a third member for forming one side of the mold and for ejecting the cast quotation therefrom, a head on said second member which extends into the 85 said mold when the same is closed, and means for connecting the said three members to the said mold operating mechanism.

3. The combination with a typecasting machine, its center pin operating lever and 90 mold members operating mechanism, of a mold for casting quotations comprising a base, two fixed and two movable mold forming members, a centering pin for closing the top of the mold, means for operating the 95 said centering pin and one of the said movable mold forming members from the said center pin operating lever, means for operating one of the said movable mold forming members to eject the cast quotation from the 100 mold and means for adjusting the latter.

4. The combination with a typecasting machine and its mold operating mechanism, 110 of a mold for casting quotations comprising a mold base forming the bottom of said mold, two opposed fixed mold members, means for adjusting one of said members, a mold blade abutment for closing the space between the said two members at the one end thereof, a mold blade adapted to operate 115 between the said two members, interchangeable mold blade heads on the said mold blade, means for operating the latter and the said abutment from the said mold operating mechanism, a lug on said mold base in the path of the cast quotations when the same are being removed from the mold and a member adapted to operate across the opening of the mold and over the said lug to remove the cast quotations from the mold.

5. A mold for casting quotations comprising a base, a mold on the same formed of a fixed mold member, an opposed fixed mold member, a mold blade abutment for closing the space between the said mold members at 125

the end thereof and provided with a closing edge, a recess formed in one of the said fixed mold member for receiving said closing edge, a mold blade adapted to operate between said mold members and a type pusher for removing the cast quotation from the said mold.

6. A mold for casting quotations comprising a base, a mold thereon formed of two 10 relatively fixed spaced mold members, a member for closing the space between the said two members at the end thereof, a mold blade adapted to operate within said mold, interchangeable heads for said mold blade, 15 a type pusher for removing the cast quotations from the said mold, a centering pin head for closing the top of said mold and extending into the same, a centering pin for supporting the said centering pin head and 20 operating the same, and means for adjusting one of the said two fixed mold members.

Copies of this patent may be obtained for five cents each, by addressing the "Commissioner of Patents, Washington, D. C."

7. A mold comprising a base having an aperture for the admission of the metal to be cast, mold forming members for forming a mold on said base around the said aperture 25 and comprising two opposed fixed mold members, a mold blade adapted to operate between the same, interchangeable mold heads on said blade for filling the space between the said two members, a mold blade 30 abutment operable at right angles to said mold blade for closing the end of the mold, means on said mold blade heads and the said base for causing the cast article to break away from the said mold members and a 35 type pusher for removing the cast article from the mold.

Signed at Newark in the county of Essex and State of New Jersey this May A. D. 1917.

SAMUEL F. GREENE.
